UNITED STATES PATENT OFFICE.

LAZARD KAHN, OF HAMILTON, OHIO, ASSIGNOR TO F. & L. KAHN & BROS.,
OF SAME PLACE.

DESIGN FOR A GAS-STOVE.

SPECIFICATION forming part of Design No. 32,752, dated May 29, 1900.

Application filed May 3, 1900. Serial No. 15,413. Term of patent 14 years.

To all whom it may concern:

Be it known that I, LAZARD KAHN, a citizen of the United States, residing at Hamilton, Butler county, Ohio, (post-office address, Hamilton, Ohio,) have invented and produced a new and original Design for Gas-Stoves, (Case F,) of which the following is a specification, reference being had to the accompanying drawing, forming part thereof, which drawing is a front perspective view of a gas-stove, showing my new design.

The new design is characterized by the rectangular body A, having at its front corners the plain curved-surfaced pilasters B, with bases C ornamented with diagonal beading and resting upon ornamental volute feet D, the space between the bases C being bridged by a skirt E, having a central curved depression flanked by concave curves, the face of the skirt being enriched with conventional foliate ornamentation, the columns being sur-

mounted by the projecting cornice F, bearing the pierced grided main top G, whose gridwork has curved margins J at its ends, the upper portion of the space between the 25 pilasters below the cornice being filled by a large rectangular door H, having its margin enriched with conventional foliate ornamentation, the lower portion of the space between the pilasters—that portion below door H and 30 above skirt E—being filled by a rectangular door I much narrower in vertical width than door H and similarly enriched at its margins.

Having described my invention, what I claim as new, and desire to secure by Letters 35 Patent, is—

The design for a gas-stove, as herein shown and described.

LAZARD KAHN.
